COMBINATION TOMBSTONE AND GRAVE MARKER

Walter A. Lewis, Syracuse, Kans.

Application February 2, 1949, Serial No. 634

Term of patent 14 years
(Cl. D79—2)

To all whom it may concern:

Be it known that I, Walter A. Lewis, a citizen of the United States, residing at Syracuse in the county of Hamilton and State of Kansas, have invented a new, original, and ornamental Design for a Combination Tombstone and Grave Marker, of which the following is a specification, reference being had to the accompanying drawing, forming part thereof.

In the drawing:

Fig. 1 is a side perspective view of a combination tombstone and grave marker, showing my new design;

Fig. 2 is a rear perspective view thereof; and
Fig. 3 is a front perspective view thereof.

I claim:

The ornamental design for a combination tombstone and grave marker, substantially as shown.

WALTER A. LEWIS.
